FIG. 2.

FIG. 4.

FIG. 5.

FIG. 6.

INVENTOR
John A. Sweitzer
BY *Wm. H. Black*
ATTORNEY

UNITED STATES PATENT OFFICE.

JOHN A. SWEITZER, OF PROVIDENCE, RHODE ISLAND, ASSIGNOR TO POWERS & MAYER MANUFACTURING CORPORATION, OF NEW YORK, N. Y., A CORPORATION OF RHODE ISLAND.

RING CONSTRUCTION.

Application filed July 7, 1922. Serial No. 573,315.

To all whom it may concern:

Be it known that I, JOHN A. SWEITZER, a citizen of the United States of America, residing at Providence, county of Providence, State of Rhode Island, have invented certain new and useful Improvements in Ring Construction, of which the following is a specification.

This invention relates to improvements in jewel settings for rings, bracelets or other articles of adornment. One of the objects of my invention is to provide a setting for jewels which can be more easily chased or otherwise decorated than settings commonly used. To accomplish this result, I provide a setting comprised of members which can be ornamented and assembled after having been ornamented. By this means rings (for instance) can be produced which are lighter in weight than those which are made in one piece, that is to say, the head and shank in one piece. I have selected a ring for illustration, but any form of ornament can be produced by means of my improvement. While my improved ornament is made up of a plurality of assembled members, they can all be securely fastened together by solder applied in such manner as to connect all of the members.

I will now proceed to describe my invention in detail, the novel features of which I will point out in the appended claims, reference being had to the accompanying drawing, wherein:

Fig. 1 is a top plan view, broken away, of a ring made in accordance with my improvement, the jewel being omitted;

Fig. 2 is a fragmentary top plan view of the shank of the ring;

Fig. 3 is a side elevation of the shank member;

Fig. 4 is a detail plan view of the head member;

Fig. 5 is a sectional view on line 5—5 in Fig. 1;

Fig. 6 is a bottom plan view of a portion of the ring, the parts making up the setting being illustrated as assembled;

Fig. 7 is a view in elevation of the assembled ring as seen in Fig. 1.

To carry my invention into practice, I employ a plurality of interconnected members, each one of which can be ornamented before being assembled. This feature is one of the principal objects of my inven-

tion. As has been stated, the parts can be made extremely light in weight which effects a great saving in cost especially when platinum is used. The parts of the setting are constructed so that they can be interconnected or meshed one with the other in such manner as to permit the application of solder at a point or points where all of the members, making up the complete ring or ornament, meet. As illustrated in Fig. 1, the ring is made up of, in this instance, three parts. The shank 13 of the ring, a head 14 and cap 15, said cap holding the jewel, should the ring be designed for a jewel. In this event the cap 15 will be provided with an opening 16 to hold the jewel. As can be seen in Figs. 1 and 5, the cap 15 includes projections or fingers 17 to enter or engage openings 18 in the head 14, said fingers being long enough to extend to a point adjacent the bottom edge 18^a of the head 14 (see Fig. 5). The body of the assembly or shank 13 is recessed as at 19 to receive the head 14. In this instance, the edge of the head 14 is scalloped; hence, the side walls 20 of the recess 19 will be shaped to conform to the scalloped edge, as indicated at 20 and 21, Fig. 1. In this instance, the bottom of the recess 19 is open and of skeleton formation, the contour of which corresponds with the scalloped edge of the head 14. In this instance, the comparatively delicate skeleton structure, indicated by 22, is reinforced by a cross-bar 23. To assemble the ring, the prongs 17 on plate 15 will be passed through the openings 18 in the head 14, and the head 14 laid upon the skeleton framework 22, a portion of the scalloped edge of the head intermeshing with the correspondingly shaped end walls of the recess 19. After the members have been assembled, solder will be applied at the point 23 where the ends of the prongs 17, edge 18^a of the head 14 and frame 22 meet. This soldering operation will effectually secure the cap 14, head 15 and shank 13 together. If desirable the opening 16 in cap 15 can be omitted and the top surface of the cap ornamented. I have not illustrated the ring as ornamented but it will be obvious that the surface of the parts can be ornamented. If desirable, the prongs 17 can be bent over and clinched to the upper portion of the cap 15.

What I desire to secure by Letters Patent is:

1. A ring comprising a body member, a plurality of superimposed head members positioned on said body member so as to have a common meeting place therewith, whereby said head members and said body member may be secured together at the common meeting place of all of said members.
2. In an ornament, a body member, a head member carried thereby having openings therein, a cap member, and projections carried by the cap member and passing through said openings.
3. In an ornament, a body member, a head member carried thereby having openings therein, a cap member, and prongs carried by the cap member engaging said openings, said prongs extending through said openings to a point adjacent the body member, whereby said prongs and body member can be soldered together thereby securing the head member in position.
4. A ring construction comprising a body member having a frame, a head portion positioned in said frame, said head portion having openings therethrough, a cap portion mounted on said head portion and having projections extending to the meeting place of the body portion and the head portion through said openings, whereby the frame, head portion, and said projections may be secured together at said meeting place.
5. In a ring, a body member, a unitary head member resting upon said body member, and a cap member engaging the head member and secured to the body member.
6. A ring construction comprising a shank having a recess therein, a head member mounted in said recess, said head member having a plurality of openings therethrough, a cap member mounted on said head member and having a plurality of projections passing through the openings in the head member and extending to a point adjacent the body member, whereby said projections can be secured to the body member thereby securing the head member in position.

JOHN A. SWEITZER.
